(57) **CLAIM**

The ornamental design for a biological array holder, as shown and described.

DESCRIPTION

FIG. 1 is a perspective view of a first embodiment of a biological array holder.

FIG. 2 is a front view of the biological array holder shown in FIG. 1.

FIG. 3 is a back view of the biological array holder shown in FIG. 1.

FIG. 4 is a side view of the biological array holder shown in FIG. 1.

FIG. 5 is a side view of the biological array holder shown in FIG. 1.

FIG. 6 is a top view of the biological array holder shown in FIG. 1.

FIG. 7 is a bottom view of the biological array holder shown in FIG. 1.

FIG. 8 is a front perspective view of a second embodiment of a biological array holder.

FIG. 9 is a front view of the biological array holder shown in FIG. 8.

FIG. 10 is a back view of the biological array holder shown in FIG. 8.

FIG. 11 is a side view of the biological array holder shown in FIG. 8.

FIG. 12 is a side view of the biological array holder shown in FIG. 8.

FIG. 13 is a top view of the biological array holder shown in FIG. 8; and,

FIG. 14 is a bottom view of the biological array holder shown in FIG. 8.

The broken lines in the drawing views are included for the purpose of illustrating portions of the biological array holder that form no part of the claimed design.

The ornamental design for a biological array holder capable of being used for analysis of biological samples.
